UNITED STATES PATENT OFFICE.

CLEM S. CLARKE AND RUPERT W. LOWE, OF SHREVEPORT, LOUISIANA.

ADJUSTER-GRIP DEVICE FOR PUMPING EQUIPMENTS.

Application filed December 1, 1922. Serial No. 604,324.

This invention relates to an improved coupling or grip device, for use in connection with the walking beams and pumping rods of pumping equipment.

5 The primary object of this invention is the provision of an improved adjuster grip or coupling device, which may be used in connection with pumping equipment for the adjustable connection of a walking beam 10 and polish rod, providing a very durable and efficient connection, in that the possibility of fracture and breakage is reduced to a minimum.

An important object of this invention is 15 the provision of an adjuster grip of the above mentioned character, which embodies means for connection to the walking beam and polish rod of pumping equipment, so that the axis of the polish rod is in aligning 20 or intersecting relation with the axis of connection of the adjuster grip with the walking beam.

Other objects and advantages of this invention will be apparent during the course 25 of the following detailed description.

In the accompanying drawings, forming a part of this specification, and wherein similar reference characters designate corresponding parts throughout the several 30 views,

Figure 1 is a fragmentary side elevation of pumping equipment, showing more particularly the association of the improved adjuster grip with the walking beam and 35 pumping rod details thereof.

Figure 2 is an enlarged fragmentary side elevation of the improved adjuster grip device.

Figure 3 is a fragmentary side elevation, 40 partly in section, showing important details of the improved adjuster grip device, this view being taken at right angles to the device as illustrated in Figure 2.

Figure 4 is a transverse cross sectional view, taken substantially on the line 4-4 of Figure 3.

Figure 5 is a cross sectional view, taken substantially on the line 5-5 of Figure 2.

Figure 6 is a plan view of the improved 50 adjuster grip device.

Figure 7 is a perspective view of a detail of a clamping unit embodied in the improved device.

In the drawings, wherein for the purpose 55 of illustration is shown but the preferred embodiment of this invention, the letter A

generally designates pumping equipment ordinarily utilized in connection with oil pumping, and which embodies the improved adjuster grip device or coupling B.

The pumping equipment A preferably includes the supporting standard 10, upon the upper end of which the walking beam 11 is oscillatively mounted intermediate its ends for operation by ordinary means 12. The 60 polish or pumping rod 15 is reciprocably mounted within the casing or tube 16, for pumping of oil and gas, in accordance with the well known manner. The improved device B is utilized for operative connection 65 of the polish or pumping rod 15 to the walking beam 11.

Referring to the improved device B, the same preferably includes a coupling or connecting rod 20, of a single piece of durable 70 metal, preferably circular in cross section, and solid throughout its length. The rod 20 includes the upper and lower portions 22 and 23 respectively, of linear or straight line formation, and connected at their junction by a diagonal relatively short portion 24, so that the axes of the upper and lower portions 22 and 23 respectively, are laterally offset in parallel relation. It is preferred that the upper portion 22 be relatively shorter than the lower portion 23, in order to allow for considerable longitudinal adjustment of the coupling B with respect to the polish or pumping rod 15. It is preferred that the terminals 27 and 28 of the 75 upper and lower portions 22 and 23 respectively be squared and reduced, in contradistinction to the cylindrical formation of the remaining portions of said coupling rod 20; thus providing shoulders 29 at the junction of the squared terminals 27 and 28 80 with the portions 22 and 23.

Means 30 is provided upon the upper portion 22 for oscillative connection to the walking beam 11, which includes the cross 85 head 32, providing the body portion 33 having the squared or polygonal shaped opening 34 vertically therethrough for receiving the squared terminal 27 of the coupling rod portion 22. In this position, the lower flat surface 34a of the cross head body 33 rests upon the shoulder 29, and at the other flat side 35 of the body 33, the extending end 36 of the coupling rod portion 22 is peened to provide a retaining head for preventing displacement of the cross head 30. Cylindrically shaped trunnions 38 and 90

39 are provided, extending in opposite directions from the body 33 and in aligning relation, providing arcuate surfaces which may receive the walking beam 11 in any 5 well known manner. Reinforcing ribs 40 are preferably provided longitudinally on the upper surfaces of the trunnions 38 and 39. The body portion 33 of the cross head 32 extends laterally of the sides of the trunnions 38 and 39, as at 41, and is vertically provided with apertures for receiving the terminals of a staple 45, which is mounted in said cross head 32 upwardly therefrom to receive a supporting hook or like element, 10 15 as can readily be understood.

Means 50 is provided at the lower end of the coupling rod portion 23, for clamping to the pumping rod 15 in adjustable manner, which includes a main portion 51, and an 20 adjustable and detachable clamp cover 52. The portion 51 is vertically provided with a polygonal passageway 54 for receiving the squared portion 28 of the coupler rod portion 23; the extending end of the squared 25 terminal 28 being peened or overturned on the lower side of the clamp portion 51, to provide a retaining head 55. The adjustable and detachable clamp jaw or cover 52 may be supported upon the body 51 of the 30 clamp device 50, as by means of bolts 57; said bolts preferably being four in number and extending transversely through said cover 52, including relatively long shanks 58 with screw threaded terminals to detachably extend transversely through the 35 clamp body portion 51 and from the side 59 of said body 51 opposite to that side which faces the clamping jaw 52. These screw threaded shanks 58 are provided with retaining nuts 60 and lock washers 61. The 40 facing surfaces 63 and 64 of the clamp body 51 and cover 52 respectively, are provided with vertical grooves or depressions in facing relation, to provide a socket opening 65 extending vertically through the clamp body 50; the axis of said socket 65, preferably being in exact aligning relation with

the axis of the coupling rod portion 22, and in intersecting relation with the axes of the cross head trunnions 38 and 39.

In assemblage, the cross head 32 is oscillatively connected to the walking beam 11, as by having the trunnions 38 and 39 thereof disposed within certain depressions or sockets in the walking beam 11, in accordance with common practice, and as is illustrated in Figures 1 and 6 of the drawings. The clamping means 50 is next adjusted properly upon the polish rod 15, according to the elevation of the pump rod 60 desired. Operation of the walking beam 11 will then effect reciprocation of the pumping rod 15 for pumping purposes. In this connection, it should be observed that the strain upon the coupling rod 20 is equally 65 distributed, and doing away with the eccentric strain imposed upon ordinary coupling rods, either incident to improper arrangement of parts, or other means not providing a sufficient factor of safety. 70

Various changes in the shape, size and arrangement of parts may be made to the form of invention herein shown and described, without departing from the spirit of this invention or the scope of the claims. 75

We claim:—

1. As an article of manufacture, a coupling rod for pumping equipment comprising upper and lower linear portions extending parallel to each other and joined by an 80 off-set portion the axis of which is diagonal with respect to the spaced parallel axes of said linear portions, the terminal portions of the upper and lower portions being polygonal in cross section. 85

2. As an article of manufacture, a coupling rod being offset intermediate its ends to provide upper and lower portions of linear formation substantially circular in cross section the axes of which are in spaced parallel relation, the terminals of said portions being squared. 90
